SEPARATION OF MIXTURES OF HYDRO-CARBONS

Paul L. Salzberg, Wilmington, Del., assignor to
 E. I. du Pont de Nemours & Company, Wil-
 mington, Del., a corporation of Delaware

No Drawing. Application May 21, 1936,
 Serial No. 81,019

6 Claims. (Cl. 196—13)

This invention relates to the separation of mixtures of hydrocarbons by selective solvent action and more particularly to the solvent refining of mineral oils.

5 It is now well known that a large proportion of the mineral oils and gasolines of today are complex mixtures of paraffinic and non-paraffinic hydrocarbons. It is frequently desirable to separate the non-paraffinic hydrocarbons from 10 the paraffinic hydrocarbons for various reasons. One of the main reasons is that the paraffinic hydrocarbons are in general more resistant to decomposition through heat and oxidation than the non-paraffinic hydrocarbons. Accordingly, 15 the oil containing the larger proportion of paraffinic constituents or, in other words, the relatively more paraffinic oils are more stable than the less paraffinic oils and hence are more desirable as lubricants and for other purposes.

20 Various methods have been proposed for separating the non-paraffinic from the paraffinic constituents of oils. One of the more common and oldest is by treatment with sulfuric acid which removes some of the non-paraffinic compounds from the oils. More recently it has been proposed to separate the non-paraffinic hydrocarbons by means of selective solvent extraction.

An object of the present invention is to provide a method for separating a mixture of paraffinic and non-paraffinic hydrocarbons into portions, one of which is relatively more paraffinic than the original mixture and the other relatively less paraffinic. Another object is the separation of relatively non-paraffinic bodies from mineral lubricating oils to produce lubricating oils of relatively high paraffinic character. A further object is the production of lubricating oils with improved viscosity-temperature curves from oils with poor viscosity-temperature curves. 30 A still further object is to provide oils with improved resistance to oxidation and decomposition and to advance the art. Still other objects will appear hereinafter.

40 These objects may be accomplished in accordance with my invention by mixing mixtures of paraffinic and non-paraffinic hydrocarbons with furfurylamine ($C_4H_9OCH_2NH_2$) to remove the non-paraffinic hydrocarbons by the selective solvent action of the furfurylamine. The oil is 45 mixed with the furfurylamine under such conditions that two layers are formed, one of which comprises the constituents which it is desired to extract from the oil, dissolved in the bulk of the solvent liquid, while the other comprises the 50 undissolved and relatively paraffinic oil in ad-

mixture with a relatively small amount of the solvent.

5 Preferably, my method comprises mixing the furfurylamine with the hydrocarbon mixture in approximately equal volumes and heating with agitation to a temperature at which the solvent and oil become completely miscible. This solution is then cooled with agitation to a temperature approximately 20° C. below the temperature of complete miscibility, allowing the mixture to stand until separation into two layers occurs, separating the layers and removing the furfurylamine from each layer. The furfurylamine may be separated from the hydrocarbons by distillation. The residue, from the layer containing the larger 10 amount of solvent, consists of a large proportion of non-paraffinic and undesirable constituents. The residue, from the layer containing the smaller amount of solvent, consists primarily 15 of the desirable paraffinic hydrocarbons.

20 In the examples given below, the selective removal of non-paraffinic constituents from a mineral oil has been measured by following the change in the viscosity-gravity constant of the oil. This constant has been described by J. B. Hill and H. B. Coates in Industrial and Engineering Chemistry, volume 20, page 641 et seq., in an article entitled "The viscosity-gravity constant of petroleum lubricating oils". If a given crude petroleum be distilled into successive fractions 25 and the specific gravities and viscosities of the several fractions determined, it will be found that they conform to the general relationship:

$$G = a + \frac{1.0752 - a \log (V-38)}{10}$$

30 in which "G" is the specific gravity at 60° F., "V" is Saybolt universal viscosity at 100° F. and "a" is the viscosity-gravity constant. These constants are lower for fractions of paraffinic crudes 35 than are the constants for fractions of the non-paraffinic crudes. The viscosity-gravity constant is, therefore, an index of the paraffinicity of an oil and a decrease in the value of this constant for a given fraction of lubricating oil indicates 40 an increase in paraffin hydrocarbon content.

45 Example 1

50 A lubricating oil distillate (with the following characteristics: viscosity at 100° F., 566 sec. Saybolt universal; specific gravity at 60° F./60° F., 0.927; viscosity-gravity constant, 0.872) was mixed with an equal volume of furfurylamine and heated with agitation to 70° C. at which temperature solvent and oil were miscible. The 55

solution was cooled to 40° C. while agitating, allowed to settle one-half hour, and the two layers withdrawn into separate containers. Furfurylamine was removed from both layers under 5 reduced pressure. Eighty percent (80%) of the original oil volume was found in the top layer and had a viscosity-gravity constant of 0.856 as compared to 0.872 for the original oil.

Example 2

10 A portion of the same crude lubricating oil distillate employed in Example 1 was heated with one and one-half times its volume of furfurylamine to 50° C. with agitation, cooled to 30° C. 15 with agitation, and allowed to stand one-half hour. The two layers which formed were treated as in Example 1, with an oil recovery in the top layer of 74%. This treated oil had a viscosity-gravity constant of 0.850 as compared to 0.872 20 for the original oil.

25 The above examples are merely illustrative of my invention. It will be readily apparent that other oils may be treated in a like manner to produce similar results. Also, in certain cases 30 N-substituted furfurylamines such as methyl furfurylamine and the like, may be substituted for the furfurylamine. Further, it is not necessary for the furfurylamine to be pure but it may be employed in a mixture with other compounds 35 and particularly with other selective solvents.

35 The conditions of application of the solvent will vary with the nature of the oil. Highly naphthenic oils will, in general, require a lower temperature to effect separation than highly 40 paraffinic oils. The temperatures employed will, in general, range from about 0° C. to about 200° C. At the higher temperatures, it may be necessary to employ pressure to prevent substantial vaporization of the solvent. The ratio of solvent 45 to oil may be varied within rather wide limits and will depend largely upon the nature of the oil being treated, the amount of non-paraffinic constituents therein and the quality of the refined oil desired. In general, the ratio of solvent to 50 oil will lie between 1 to 10 and 5 to 1 parts by volume.

50 While distillation is the preferred method for separating the solvent from the oil, other means may be employed such as conversion of the 55 amine solvent into an insoluble salt or extraction of the amine with a solvent which is a non-solvent for the oil. My process may be applied to a raw distillate or to a partially refined product, or to cracked gasolines, cracked naphtha and the like. Under certain conditions, as for example in the case of oils with high sulphur content or poor sludging characteristics, it may be desirable to supplement the extraction treatment with the usual acid, alkali, doctor or clay treatment, applied either before or after the solvent 60 extraction.

65 While I have disclosed the preferred embodiments of my invention and the preferred modes of carrying the same into effect, it will be readily apparent to those skilled in the art that many variations and modifications may be made therein without departing from the spirit of my in-

vention. Accordingly, the scope of my invention is to be limited solely by the appended claims construed as broadly as is permissible in view of the prior art.

5 I claim:

1. The method of treating a normally liquid hydrocarbon mixture containing relatively paraffinic and relatively non-paraffinic compounds which comprises extracting the hydrocarbon mixture with a furfurylamine to separate the relatively non-paraffinic compounds from the relatively paraffinic compounds. 10

2. The method of treating a normally liquid hydrocarbon mixture containing relatively paraffinic and relatively non-paraffinic compounds 15 which comprises mixing a furfurylamine with the hydrocarbon mixture, causing the resulting mixture to separate into two layers and separating the layers, whereby the relatively non-paraffinic compounds are separated from the relatively paraffinic compounds. 20

3. The method of treating a normally liquid hydrocarbon mixture containing relatively paraffinic and relatively non-paraffinic compounds 25 which comprises mixing a furfurylamine with the hydrocarbon mixture, heating the resulting mixture to a temperature where the furfurylamine becomes completely miscible with the hydrocarbon mixture, cooling to about 20° C. below the 30 temperature of complete miscibility and causing the mixture to separate into two layers, separating the two layers, and removing the furfurylamine from each layer, whereby the relatively non-paraffinic compounds are separated from the relatively paraffinic compounds. 35

4. The method of treating a normally liquid hydrocarbon mixture containing relatively paraffinic and relatively non-paraffinic compounds 40 which comprises extracting the hydrocarbon mixture with furfurylamine to separate the relatively non-paraffinic compounds from the relatively paraffinic compounds. 45

5. The method of treating a normally liquid hydrocarbon mixture containing relatively paraffinic and relatively non-paraffinic compounds 50 which comprises mixing furfurylamine with the hydrocarbon mixture, causing the resulting mixture to separate into two layers and separating the layers, whereby the relatively non-paraffinic compounds are separated from the relatively paraffinic compounds. 55

6. The method of treating a normally liquid hydrocarbon mixture containing relatively paraffinic and relatively non-paraffinic compounds 60 which comprises mixing furfurylamine with the hydrocarbon mixture, heating the resulting mixture to a temperature where the furfurylamine becomes completely miscible with the hydrocarbon mixture, cooling to about 20° C. below the temperature of complete miscibility and causing 65 the mixture to separate into two layers, separating the two layers, and removing the furfurylamine from each layer, whereby the relatively non-paraffinic compounds are separated from the relatively paraffinic compounds. 70

PAUL L. SALZBERG.
